UNITED STATES PATENT OFFICE.

NICHOLAS H. PRILEY, OF DULUTH, MINNESOTA.

BOX-LID SUPPORT.

No. 882,713.

Specification of Letters Patent. Patented March 24, 1908.

Application filed May 3, 1907. Serial No. 371,630.

To all whom it may concern:

Be it known that I, NICHOLAS H. PRILEY, a citizen of the United States, residing at Duluth, in the county of St. Louis and State of Minnesota, have invented certain new and useful Improvements in Box-Lid Supports, of which the following is a specification, reference being had therein to the accompanying drawing.

10 My invention relates to improvements in box lid supports, and pertains more particularly to that class used in connection with cigar boxes.

15 The object of my invention is to provide a device of this character that can be applied to the box and perform its function with the least possible amount of disfigurement and clumsy effect to the box.

20 Another object of my invention is to provide a device of this character which is of the simplest construction, and one requiring a minimum amount of material, thus producing a more simple, cheap and effective support.

25 In the accompanying drawings, Figure 1, is an interior perspective view of a cigar box partly broken away, showing the support applied. Fig. 2, is a rear view of Fig. 1, and Fig. 3, is an enlarged side elevation of the 30 improved support.

Referring now to the drawings, 1 represents a piece of wire or like material, having its upper end bent at right angles, as indicated at 2, forming the horizontal portion 3 which is bent around, as at 4, and extended back as at 5, parallel with the portion 3, thus forming a loop between which the edge of the box lid is forced, and firmly clamped. The vertical portion or piece of wire 1 is bent at 40 its lower end and provided with the upwardly extending oblique portion 6 forming an acute angle, and which has its upper end bent into a short horizontal loop 7, and the wire is continued downwardly into a vertical portion 8. 45 As shown, the entire support is made of a single piece of wire or metal, thus making the manufacture thereof very cheap, and by the specific means of arranging the several loops, a support to accomplish the desired results, is 50 formed of much less material, thus lessening the cost of the article.

In application, the lid of the box is forced between the horizontal loop formed by the

horizontal portions 3 and 5, and is firmly held between the same. The vertical portion 1 extends down below the upper end of the box, and the oblique portion extends upwardly, while the loop 7 extends over the upper edge of the box, and around the edge of the cover, and the vertical portion 8, fitting tightly into the corner of the box, and firmly clamped by the flexibility of the wire, thus supports the cover in a vertical position. If desired, the vertical portion of the wire might be bent laterally intermediate its end to throw the cover at a slight angle to the box.

Having thus described my invention, what I claim and desire to secure by Letters Patent, is:—

1. A box lid support consisting of a wire 70 having a single lateral loop at its upper end for engagement with the lid of the box, an angularly-disposed loop at the lower end for engagement with the body of the box, and an offset portion for resting upon the edge of the 75 end of the box.

2. A box lid support consisting of a vertical wire having a single laterally-disposed loop at its upper end for engaging the lid of the box, and at its lower end an upwardly-extending oblique portion having a horizontal 80 loop terminating in a downwardly-extending vertical portion.

3. A box lid support, comprising a vertical wire having a single laterally-disposed loop 85 at its upper end for engaging the lid of the box, and its lower end bent upwardly at an acute angle and having a horizontal small loop formed therein, and the wire terminating in a downwardly-extending vertical portion. 90

4. A box lid support, comprising a vertical wire having a single laterally-disposed loop at its upper end for engaging the lid of the box, and its lower end bent upwardly at an 95 acute angle and having a horizontal small loop formed therein, and its outer end in a vertical line with the outer end of the laterally-disposed loop and the wire terminating in a downwardly-extending vertical portion. 100

In testimony whereof I affix my signature in presence of two witnesses.

NICHOLAS H. PRILEY.
